[57] CLAIM

The ornamental design for a tire, substantially as shown and described.

DESCRIPTION

FIG. 1 is a perspective view, partly schematic, of a tire showing the new design, it being understood that the tread pattern is repeated throughout the circumference of the tire as shown schematically by solid lines;

FIG. 2 is an enlarged fragmentary front elevational view thereof; and

FIG. 3 is an enlarged fragmentary side elevational view thereof.

FIG. I

FIG. 2

FIG. 3
